A. FIELD.

DRAFT TONGUE EXTENSION.

APPLICATION FILED MAY 2, 1918.

1,297,553.

Patented Mar. 18, 1919.

UNITED STATES PATENT OFFICE.

ALVAN FIELD, OF ALINE, OKLAHOMA.

DRAFT-TONGUE EXTENSION.

1,297,553.

Specification of Letters Patent. Patented Mar. 18, 1919.

Application filed May 2, 1918. Serial No. 232,106.

To all whom it may concern:

Be it known that I, ALVAN FIELD, a citizen of the United States, residing at Aline, in the county of Alfalfa and State of Oklahoma, have invented certain new and useful Improvements in Draft-Tongue Extensions, of which the following is a specification.

This invention relates to improvements in attachments for draft tongues to extend 10 the same at the forward end to provide for the increased space required when a double team or four horses are employed.

Another object of the invention is to provide a device of this character which 15 may be readily adapted without material structural change to draft tongues of various forms and sizes, and without structural change in the draft tongue.

With these and other objects in view, 20 the invention consists in certain novel features of construction, as hereinafter shown and described and then specifically pointed out in the claims; and in the drawings illustrative of the preferred embodiment of the 25 invention—

Figure 1 is a plan view of a draft tongue with the swingle trees and evener devices for four horses attached and with the improvement applied to the forward end of 30 the tongue.

Fig. 2 is a side elevation of the forward portion of the tongue and its attachment.

Fig. 3 is an enlarged perspective view of a portion of the forward end of the 35 draft tongue.

Fig. 4 is an enlarged detached perspective view of the improved extension device.

The draft tongue is represented as a whole at 10 and is provided with the usual device 40 pending neck yoke stop 11 spaced from the forward end. The ordinary tongue is provided with a strap 12 attached to its upper and lower faces and projecting in advance of the end of the tongue into a loop represented at 13. When two horses are applied to the double tree and a single pair of the swingle trees, the distance between the double tree and the yoke neck stop 11 corresponds to the horses, and when four 45 horses are to be employed and a draft beam represented at 14 is used in addition to the usual double tree 15, the swingle trees represented at 16 are moved forwardly a considerable distance, consequently the ordinary neck yoke stop is too near to the 50 swingle trees to receive the neck yoke, and

the object of the present invention is to provide an extension to the forward end of the tongue having a supplemental neck yoke stop, so that the neck yoke of the teams 5 will be at the proper distance from the swingle trees. When the double team or four horses are employed the neck yoke devices usually occupy more space than the single neck yoke, consequently the extension 6 will likewise be of greater length than the advanced position of the swingle trees. The improved attachment includes a supplemental tongue or block member 17, preferably substantially of the same size transversely as the main tongue 10. Attached to the upper and lower faces of the member 17 is a strap 18 extending over the forward end of the block and rearwardly of the same, the rearwardly extending portion being 75 projected upwardly and rearwardly in an oblique direction as represented at 19 and thence horizontally as represented at 20, the oblique portion extending between the loop 13 of the tongue and the rear end of 80 the block 17, and the horizontal portion 20 bearing over the upper side of the strap 12. The lower portion of the strap 18 is extended downwardly to form a neck yoke stop 21 corresponding to the stop 11 of the tongue. A 85 U-shaped strap represented as a whole at 22 bears against the side faces of the block 17 with its forward end curved to form a loop 23 similar to the loop 13 of the tongue. The side portions of the strap 22 extend 90 rearwardly of the block for a considerable distance and are designed to bear against the side faces of the forward portion of the tongue 10. At their rear ends the side members of the strap 22 are coupled by a strap 95 24 bearing over the upper side of the tongue 10, and likewise coupled intermediate their ends by a downwardly directed strap 25. The strap 24 operates to prevent downward displacement of the side members 22 at the 100 rear ends while the strap 25 prevents upward displacement of the attachment. The strap 25 as noted by reference to Fig. 2 bears against the neck yoke stop 11 of the tongue and thus prevents rearward movement of the attachment. The overhanging portion 20 of the strap 18 bearing upon the upper face of the tongue effectually prevents downward displacement of the attachment. The rearwardly extended side members of 110 the strap 22 closely engage the sides of the tongue 10, and the whole attachment is held

by friction only in position. It will be noted by this arrangement that the attachment is held from rearward movement and vertical and lateral movement, but is held by friction only from forward movement. Frictional engagement between the attachment and the tongue is sufficient to prevent forward displacement, as the strains when the device is in use are rearwardly only as 10 in the case of the ordinary neck yoke.

The improved device is simple in construction, can be inexpensively manufactured, and operates effectually to provide an extension for the draft tongue when 15 required.

Having thus described the invention, what is claimed as new is:

1. An attachment for draft tongues comprising a body, a strap including a portion 20 engaging beneath said body and extended obliquely and thence parallel to the longitudinal plane of the same, straps engaging the side faces of the body and extending in spaced relation rearwardly thereof, an upwardly directed loop connecting said spaced strap members at their free ends, and a downwardly directed loop connecting said spaced strap members intermediate their extended portions, said body being adapted 25 to be disposed in advance of a draft tongue with the straps and loops bearing over the same.

2. An attachment for draft tongues comprising a body having means for supporting a neck yoke, straps extending rearwardly of the body in spaced relation and connected at their rear ends by an upwardly directed loop and intermediate their ends by a downwardly directed loop, and a 30

member extending obliquely and thence 40 longitudinally of the body and between the spaced straps, said body being adapted to be disposed in advance of a draft tongue with the straps and loops bearing over the same and the intermediate loop adapted to engage 45 the neck yoke stop of the draft tongue.

3. An attachment for draft tongues comprising a supplemental tongue of substantially the same size transversely as the main tongue and adapted to be disposed in advance of the main tongue, said supplemental tongue being freely separable from the main tongue and provided with a depending neck 50 yoke stop and spaced longitudinal arms adapted to embrace the main draft tongue. 55

4. The combination with a draft tongue including a neck yoke stop, of an extension engaging the end of the draft tongue and freely separable therefrom, said extension forming a continuation of the draft tongue 60 and being provided with a supplemental neck yoke stop.

5. The combination with a draft tongue of a supplemental tongue of substantially the same size transversely as the main 65 tongue fitting over the end of the main tongue and freely separable therefrom, said supplemental tongue being disposed in longitudinal alignment with the draft tongue and provided with a depending neck yoke 70 stop, and means carried by the supplemental tongue engaging the walls of the main draft tongue for preventing accidental displacement of said supplemental tongue.

In testimony whereof I affix my signature. 75
